UNITED STATES PATENT OFFICE.

SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

LOCK.

1,392,707.

Specification of Letters Patent.

Patented Oct. 4, 1921.

Application filed January 17, 1920. Serial No. 352,066.

To all whom it may concern:

Be it known that I, SAMUEL SEGAL, a citizen of the United States, and a resident of New York, in the county of New York and 5 State of New York, have invented certain new and useful Improvements in Locks, of which the following is a specification.

My invention has for its object the production of a lock which shall be adapted to 10 be applied to a swinging door and which shall be of simple construction and of positive operation and which shall operate, when in locked position, to effectively prevent an unauthorized entrance through the door 15 either by "jimmying" the lock or otherwise.

The invention consists briefly and essentially in the provision of a casing or other support fastened to the door and containing the locking mechanism and which shall contain 20 one or more locking bolts adapted to be actuated and to extend through the end wall of the casing and to interlock with a keeper fastened to the door frame as well as with a stationary bar rigidly fastened or 25 connected to the casing and means on the keeper adapted to interlock with the connecting-piece or bar joining the stationary bar and casing together.

A practical embodiment of the invention 30 is illustrated in the accompanying drawing and will be more particularly described in the following specification having reference thereto, from which other and further objects and advantages of the invention will 35 appear, the invention being thereafter specified in the claims appended hereto.

In the accompanying drawing:

Figure 1 is a front elevation of my improved lock as applied to a door.

Fig. 2 is a horizontal section on the line 2-2 of Fig. 1.

Fig. 3 is a rear elevation of the lock with its cover plate removed.

Fig. 4 is a horizontal section on the line 4-4 of Fig. 1.

Fig. 5 is a vertical cross-section on the line 5-5 of Fig. 1.

Fig. 6 is a vertical cross-section on the line 6-6 of Fig. 3.

Fig. 7 is a rear perspective view of the lock casing.

Fig. 8 is a perspective view of the keeper.

Referring more particularly to the several figures of the drawing:

1 indicates the front wall of a casing, 2 an end wall and 3 a removable cover plate adapted to rest on suitable lugs 4 fastened to the side walls of the casing, and to be held in position on the lugs by a screw 5, as shown, engaging a post 6 fastened to the front wall 55 1. Said casing is adapted to be fastened to a door 7 by suitable screws 8 passing through the front wall 1 and the cover plate 3 (see Fig. 6) with the wall 2 preferably in alignment with the space between the door and 60 the door frame which is indicated at 9.

10 indicates a locking bolt mounted in the casing and horizontally slidable therein on the post 6. Said locking bolt is provided with suitable locking elements 11 adapted to 70 extend through perforations 12 with which the end wall of the casing is provided and which provide guides and supports for the locking elements. Said locking bolt is also provided with a notch 13 adjacent its end 75 and with outwardly extending lugs 14 at either side of said notch and having opposed inclined surfaces as illustrated. Pivoted on the locking bolt as at 15, is a tumbler pawl 16 having a shoulder 17 on its lower side 80 which is adapted to engage the post 6, said tumbler pawl being also provided with a hooked end 18 adapted to fit within the notch 13. The opposite end of the tumbler pawl is provided with a leaf spring 19 one 85 end of which is fastened thereto, the opposite end of said pawl engaging a pin 20 on the locking bolt. The action of said leaf spring 19 tends to retain the hooked end of the tumbler pawl in the notch 13 intermediate the 90 lugs 14 in an obvious manner and the shoulder 17 in engagement with the post 6.

21 indicates a knob mounted in the front wall of the casing and operable from the inside of the door and to the shank of which 95 is attached an annular plate 22 provided with operating arms or fingers 23. A tumbler barrel 24 of a conventional form of cylinder lock is embedded in the door 7 and the shank 25 thereof extends through the 100 removable cover plate 3 and carries on its end an annular plate 26 provided with operating arms or fingers 27.

28 indicates a stationary rigid bar which

is fastened to the end wall 2 of the casing by a connecting bar 29, provided with a hole 30, as well as by the connecting bars 31 and 32. The end wall 2, bar 28 and connecting bars 31 and 32 are preferably all cast as an integral structure for the purpose of strength and convenience of manufacture. The said rigid bar 28 is provided with holes 33 in alignment with the perforations 12 in the end wall 2, said holes being adapted to receive the ends of the locking elements 11 of the locking bolt when said locking elements are in closed or locked position.

34 and 35 indicate the flanges of a keeper 15 forming an angle piece which are countersunk in the edge of the door frame and held by screws as illustrated and 36 indicates outwardly extending perforated ears preferably integral with said flanges. When the door is closed and the lock is in locked position the perforated ears 36 extend or protrude within the spaces formed by the end wall 2, the rigid bar 28, the connecting bar 29 and upper and lower bars 31 and 32 and 25 the locking elements 11 of the locking bolts extend through the perforations in the end wall 2, through the perforations in the ears 36 and into the holes 33 of the rigid bar 28. Moreover an outwardly extending pin or 30 stud 37 with which the keeper is provided fits within the hole 30 of the connecting bar 29. These various parts interlocking with each other, provide a secure and effective locking means for the door as is manifest.

35 The locking bolt may be actuated either by turning the knob 21 on the inside of the door and thereby revolving the operating arms 23 of the annular plate 22 or by turning a key in the tumbler barrel 24 from 40 without the door to effect a revolving of the arms 27 of the annular plate 26, each being operable independently of the other. Referring particularly to Fig. 3 showing the locking bolt in closed or locked position with 45 the shoulder 17 engaging the right-hand side of the post 6 and held thereby the spring 19, it is obvious that the bolt cannot be withdrawn or brought into unlocked position until the shoulder 17 is released from 50 its engagement with the right-hand side of said post 6. This is effected by revolving the right-hand operating arm 27 in a counter-clockwise direction (or the operating arm 23 as the case may be) to cause the end 55 of said arm to engage the hook 18 of the tumbler pawl thereby raising said tumbler pawl against the action of the leaf spring 19 and lifting the shoulder 17 from its engagement with the right-hand side of 60 post 6. Further movement of the operating arm 27 in the same direction causes the end of the same to engage the inclined side of the left-hand lug 14 to draw the locking bolt into unlocked position. As soon as it reaches

this position the shoulder 17 falls into engagement with the left-hand side of post 6 due to the action of the leaf spring 19, the locking bolt being shown in dotted lines in Fig. 3 just before it has reached unlocked position. The reverse operations are necessary to throw the locking bolt from unlocked into locked position, but the particular mechanism just described and its operation are old in the art and it is thought require no further detailed explanation. 75

I am aware that it has been proposed to employ a separate bar somewhat similar in configuration to my improved rigid bar 28 which has been made movable and which has in fact been a part of the locking bolt 80 itself and has carried the locking elements which have been made an integral portion thereof. In practice, however, a lock of this character is impractical and weak for the reason that when it is "jimmied" the part 85 corresponding to the shoulder 17 described herein must stand all the strain of the jimmying and the lock soon gives way. In my case the lock is jimmie-proof and the whole lock casing is subjected to an equal strain if 90 it is attempted to jimmie or pry off the same and if the casing is partially moved, the rigid bar acts as a stop or obstruction against which the jimmie strikes to prevent further movement or dislodging of the 95 casing.

What I claim as my invention is:—

1. In a lock, a casing, a bar, a connecting bar rigidly joining said first-named bar and said casing, a keeper, a locking bolt adapted to interlock with said keeper and said first-named bar and means on said keeper adapted to interlock with said connecting bar. 100

2. In a lock, a casing, a bar, a connecting bar intermediate said first-named bar and said casing and provided with a hole therein, a keeper, a locking bolt adapted to interlock with said first-named bar and said keeper and a stud on said keeper adapted 110 to enter and interfit with a hole of the connecting bar.

3. In a lock, a casing having a perforated end wall, a bar rigidly fastened to said end wall and provided with holes therein, a stationary bar intermediate said end wall and said rigid bar and provided with a hole therein, a keeper provided with perforated ears and a locking bolt adapted to slide through the perforated end wall of the casing, through the perforated ears of the keeper and into the holes in said bar and means fastened to and extending transversely from said keeper adapted to enter the hole in said stationary bar. 115

4. In a lock, a casing having a perforated end wall, a bar provided with holes therein, a connecting bar rigidly joining said first-

named bar and the end wall of the casing and provided with a hole therein, a keeper having perforated ears adapted to extend in the space between said first-named bar and said end wall, a horizontally slidable locking bolt within said casing adapted to operate through the perforated end wall, the perforated ears of the keeper and in the holes of the first-named bar and a stud on the keeper adapted to enter the hole of 10 said connecting bar.

Signed at New York, in the county of New York and State of New York, this 16th day of January, A. D. 1920.

SAMUEL SEGAL.
